US0D1049065S

(12) **United States Design Patent** (10) **Patent No.:** **US D1,049,065 S**
(45) **Date of Patent:** **** Oct. 29, 2024**

(54) **SEMICONDUCTOR PACKAGE**

(71) Applicant: **JMJ Korea Co., Ltd.**, Bucheon-si (KR)
(72) Inventor: **Yun Hwa Choi**, Bucheon-si (KR)
(73) Assignee: **JMJ KOREA CO., LTD.**, Bucheon-si (KR)

(**) Term: **15 Years**

(21) Appl. No.: **29/798,851**

(22) Filed: **Jul. 12, 2021**

(51) **LOC (14) Cl.** 13-03

(57) **CLAIM**

The ornamental design for a semiconductor package as shown and described.

DESCRIPTION

FIG. 1 is a front view of a semiconductor package showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines illustrate portions of the article and environmental subject matter that form no part of the claimed design.
